UNITED STATES PATENT OFFICE.

MORRIS STETTNER, OF BROOKLYN, NEW YORK.

COMBINED RADIO AND PHONOGRAPH CABINET CONSTRUCTION.

Application filed January 26, 1924. Serial No. 688,762.

To all whom it may concern:

Be it known that I, MORRIS STETTNER, a citizen of the United States, and a resident of the city of New York, borough of Brooklyn, in the county of Kings and State of New York, have invented a new and Improved Combined Radio and Phonograph Cabinet Construction, of which the following is a full, clear, and exact description.

The invention relates to a new and improved cabinet combining a phonograph and a radio apparatus, and has for an object the provision of a simple and efficient means whereby a common horn can be used to transmit either phonographically produced sounds or radio broadcasting.

Another object concerns the provision of a simple and efficient construction whereby by the simple manipulation of a single element the ordinary phonograph horn can be connected alternately to a radio loud speaker or to the phonograph tone arm.

The invention is illustrated in the drawings, of which—

25 Figure 1 is a plan view of the cabinet; Fig. 2 is a section taken on the line 2—2 of Fig. 1;

Fig. 3 is a section taken on the line 3—3 of Fig. 2; and

30 Fig. 4 is a section taken on the line 4—4 of Fig. 2.

The form of the invention shown in the drawings is a preferred form, although it is understood that modifications in the construction and arrangement of the parts and in the character of the materials used may be adopted without departing from the spirit of the invention as set forth in the appended claims.

40 In the commercial application of radio to-day it is common practice to combine a radio apparatus with a phonograph apparatus in the same cabinet and to utilize the same horn for both reproductions. In order to simplify the construction and mechanism whereby the same horn can be utilized I have provided the apparatus set forth.

In its essentials the apparatus includes a construction in which a main sound passage 1 is established. This sound passage connects directly with a phonograph horn (not shown) and ordinarily extends upwardly from beneath the platform 2 on the phonograph, through the aperture 3 therein above and in registration with which there is disposed the usual tone arm 4. The body por-

tion 5 which contains the main sound passage 1 is laterally apertured, as shown at 6, to connect with an auxiliary body portion 7 containing an auxiliary sound passage 8 in the end of which a radio loud speaker device or amplifier 9 can be disposed.

It will, therefore, be seen that as thus far described the invention includes the association of a main sound passage 1 with the two auxiliary passages, namely, the passage 8 and the passage 10, formed within the tone arm 4. It is obvious that when sound is being transmitted from one of these auxiliary passages into the main passage to be transmitted through the phonograph horn it is not desirable to have the other auxiliary passage connected with the main sound passage. To this end, I provide a pair of slidable members 11 and 12 in the form of slidable plates which move in suitable slots formed in association with the body portions 5 and 7, and by reason of their disposition are disposed to be interposed respectively between the main sound passage 1 and the auxiliary sound passages 10 and 8. The slidable member 11 is provided with an aperture 13, and the slidable member 12 is provided with an aperture 14, so that in one position of the slidable members their apertures are brought into alignment between the main sound passage 1 and their respective auxiliary passages. The apertures in these slidable members, however, are so disposed that they will not both be in registration with their respective sound passages at the same time.

As shown in Fig. 3, the slidable members 11 and 12 are connected at their ends to an operating plate 15 to which an arm 16 is connected, this arm extending forwardly through the slot 17 in the table or platform 2 and provided on its upper end with a knob 18 whereby the arm can be manipulated to slide back and forth in the slot 17 and through this action to move the plates 11 and 12. In the position shown in the drawings, the member 11 is disposed with its aperture 13 in alignment between the main sound passage 1 and the auxiliary sound passage 10 in the tone arm 4, whereas the member 12 is disposed with its aperture 14 out of alignment between the main passage 1 and the auxiliary passage 8. In this position, therefore, the horn is connected to the phonograph tone arm, whereas it is obvious that if the knob 18 is moved to the other end

2
of the slot 17 the connection between the main sound passage 1 and the auxiliary passage 10 will be interrupted and the connection between the main sound passage 1 and the auxiliary passage 8 will be established through the aperture 14 so that the phonograph horn can be used to transmit sound produced by the radio loud speaker device 9. This apparatus, excepting for the knob 18, is disposed beneath the platform or table 2 and is hidden from view. The only visible part of the apparatus is the knob 18 by means of which the slidable plates are operated after they have been assembled. Their movement is effected by the simple sliding back and forth of the knob 18 to effect the registration desired.

It is desirable to provide the opposite surface of the slidable members with material 20 19, such as felt, whereby the sliding engagement between the sides of the slidale members and the walls of the body portions through which they pass may be made as snug as possible to eliminate the leakage of sound therethrough and to prevent the movement of the plate from being too free.

What I claim is:—

1. A combined radio and phonograph cabinet construction, which comprises a body 20 30 portion having a main sound passage therein, a plurality of other body portions hav-

ing auxiliary sound passages therein connected to the main sound passage, slidale apertured members in said body portions adapted to be interposed between the main passage and the auxiliary passages, and means for moving said slidale members simultaneously to alternately register their respective apertures between the main sound passage and the respective auxiliary passages whereby the flow of sound between the main passage and the auxiliary passages can be selectively controlled.

2. A combined radio and phonograph cabinet construction, which comprises a body portion having a main sound passage, a body portion having an auxiliary sound passage to which a phonograph tone arm is connected, a second auxiliary body portion having a sound passage therein to which a radio 50 loud speaker device can be attached, a slidale plate in each of said body portions to be interposed between the main sound passage and the respective auxiliary passages, each of said plates being apertured, and means for operating said plates simultaneously, the apertures in said plates being so relatively disposed therein that only one can be in alignment between the main sound passage and its auxiliary passage at the same time.

MORRIS STETTNER.
